Primary Examiner — R. Johnson(74) *Attorney, Agent, or Firm* — K. David Crockett, Esq.; Paul J. Backofen, Esq.; Crockett & Crockett, PC(57) **CLAIM**

The ornamental design for a stringed instrument, as shown and described.

DESCRIPTION

FIG. 1 is a left-front perspective view of a stringed instrument showing our new design.

FIG. 2 is a right-rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a bottom plan view thereof; and,

FIG. 8 is a top plan view thereof.

Broken lines in the attached drawings are included for the purpose of illustrating portions of the stringed instrument and form no part of the claimed design.
